POPCORN COATING MACHINE

Fred H. Groen, Jr., Oak Park, Ill., assignor to Groen
Mfg. Co., Elk Grove Village, Ill., a corporation of
Illinois

Filed Oct. 5, 1959, Ser. No. 57,816

Term of patent 14 years

(Cl. D55—1)

Fig. 1.

Fig. 2.

Fig. 3.

Fig. 4.

Fig. 1 is a perspective view of the popcorn coating machine with the caramel container seated upon its heating means and the popcorn mixing container pivoted to its discharging position;

Fig. 2 is a front elevational view of the machine;

Fig. 3 is a plan view of the machine;

Fig. 4 is an end elevational view of the machine; and

Fig. 5 is a rear view of the machine with the popcorn mixing container pivoted upwardly to its mixing position.

The undisclosed side of the machine is substantially plain.

The dominant features of my design reside in the portions shown in full lines.

I claim:

The ornamental design for a popcorn coating machine, as shown and described.
